H. SEARLE.
OIL EJECTOR.

No. 61,571.

Patented Jan. 29, 1867.

Henry Searle

United States Patent Office.

HENRY SEARLE, OF ROCHESTER, NEW YORK.

Letters Patent No. 61,571, dated January 29, 1867.

IMPROVEMENT IN OIL EJECTORS.

The Schedule referred to in these Letters Patent and making part of the same.

TO ALL WHOM IT MAY CONCERN.

Be it known that I, HENRY SEARLE, of Rochester, in the county of Monroe, and State of New York, have invented a new and useful Improvement in Pumps; and I do hereby declare that the following is a full and exact description thereof, reference being had to the accompanying drawings, and letters of reference marked thereon.

The nature of my invention consists in so combining two or more oil ejectors, with an air-pump or steam boiler, by means of suitable pipes and valves, as that any two of the ejectors may be operated by the one pump or boiler at the same time, by passing alternately the steam or compressed air used in the one, directly to the other, the chamber of each ejector becoming thereby alternately a compressed-air chamber and an exhausted receiver.

To enable others skilled in the art to make and use my invention, I will proceed to describe its construction and operation, by referring to the accompanying drawings, in which—

A shows a pipe, which is connected with the chamber, *a*, of my ejector No. 1, in a well. B, a pipe connected with the chamber, *b*, of my ejector No. 2, in a well. The pipes C D connect respectively with the induction and exduction apertures of the piston-chamber of an air-pump, or, where steam is used, with a steam boiler, in which case the one pipe, D, is alone connected with the boiler, the pipe, K, being left as an escape pipe. E F G and H show stop-cocks, by means of which the current of air is changed from one ejector to the other. Valves or other mechanical devices for arresting, controlling, and regulating the currents of air or steam, may be substituted for the ordinary stop-cocks shown in the drawings, and two may be made to perform the necessary functions of my apparatus instead of four, although I prefer four as hereafter described. In using air I contemplate keeping the air-pump constantly working; then by opening the cocks E and H, and closing all others, the air in the chamber *b* of the ejector No. 2 is exhausted, and the air forced into the chamber *a* of the ejector No. 1, making the chamber *b* an exhausted receiver, and the chamber *a* a compressed-air chamber. The cocks E and H are then closed, and the cocks G and F are opened; the air-pump still working in the same manner. The chamber, *a*, of the ejector No. 1 is exhausted, and the air forced into the chamber *b* of the ejector No. 2, making the chamber *a* the exhausted receiver, and the chamber *b* the compressed-air chamber, and so making the chamber of each ejector alternately a compressed-air chamber and exhausted receiver. I show a stop-cock, through which a supply of air is taken from the atmosphere when required. Now it will be seen that by connecting the piston-chamber of an air-pump with the induction and exduction pipes C and D, and keeping the air-pump constantly at work, the stop-cocks, being in the proper position, the air is taken from the chamber of one ejector and forced into the chamber of the other ejector; and by opening and closing the stop-cocks, as before described, the current of air is changed from one ejector to the other, and the same air used in one ejector is also used in the other, thereby making the chamber of each ejector alternately a compressed-air chamber and exhausted receiver. It will also be seen that when a supply of air is required, by closing the stop-cocks H, G, and F, and opening the cocks I and E, the air is taken in from the atmosphere at K, and forced into the chamber of the ejector No. 1. By changing the cocks the air may be forced into the ejector No. 2. When I use steam, I first close cocks F and G, and allow the steam to pass down pipe A, then close E, and open G, allow steam to pass into the pipe B, after which I close cocks H and G, opening F, steam to pass from boiler under pressure into pipe B. In mean time the condensation of steam in ejector *a* will fill with oil, to be expelled at next admission of steam, which is obtained by operating cocks as above described.

I am aware of a patent issued to F. S. Pease, on March 28, 1865, for ejecting oil or other fluids from wells and other deep places, by intermittent pulsating action or repeated vibration of a confined body of air or other fluid.

I hereby disclaim anything patented by him, but what I do claim as my invention, and desire to secure by Letters Patent, is—

1. The arrangement of two or more ejectors (for raising oil or other fluids from wells and other deep places) with each other, and with pipes and cocks or valves, substantially in the manner and for the purpose described.
2. The arrangement of two or more cocks or equivalent valves E F G and H, in combination with the pipes A and B, for the purpose of changing the action of a column of compressed air or other fluid alternately from one ejector to another, substantially in the manner and for the purpose described.
3. The combination of the pipes A B C D, and cocks or valves E, F, G, H, with independent ejectors *a* and *b*, for the purpose of making the chamber of each ejector act alternately as a compressed-air chamber and as an exhausted receiver.

HENRY SEARLE.
